Harrison H. Boyce.

BY

Howard Quincy Moore his ATTORNEY

UNITED STATES PATENT OFFICE.

HARRISON H. BOYCE, OF FOREST HILLS, NEW YORK.

MEANS FOR INTRODUCING TEMPERATURE-RESPONSIVE ELEMENTS INTO ENGINE-COOLING SYSTEMS.

Application filed April 19, 1918. Serial No. 229,581.

To all whom it may concern:

Be it known that I, HARRISON H. BOYCE, a citizen of the United States, residing at Forest Hills, in the county of Queens and 5 State of New York, have invented certain new and useful Improvements in Means for Introducing Temperature-Responsive Elements into Engine-Cooling Systems, of which the following is a specification.

This invention relates to a construction for mounting the temperature responsive elements of indicating instruments or other devices in ducts and more particularly in the piping of engine cooling systems. In 15 my Patent No. 1,206,783 I have disclosed an invention relating to the indication of the condition of internal combustion engines of vehicles, said invention being characterized by the introduction into the engine cooling 20 system, at a point where the cooling water has been heated by contact with the engine cylinders, of a temperature responsive element controlling indicating device readable by the driver. A preferred location for 25 such temperature responsive element, as illustrated in said patent, is in the return pipe leading the heated cooling water from the cylinder jackets to the radiator. The present invention is especially adapted to 30 provide means for mounting a temperature responsive element in this location although the invention may be utilized in any analogous situation.

In the accompanying drawings which 35 form a part of this specification Figure 1 is a diagrammatic side elevation illustrating the engine and cooling system of an automobile, aeroplane or other vehicle and showing a preferred application of the invention 40 thereto.

Figure 2 is a longitudinal sectional view of a duct section having a temperature responsive element introduced thereinto in accordance with the invention.

Figure 3 is an end view of the bulb fitting with a bulb therein.

Figure 4 is a horizontal section on line IV—IV of Figure 3.

Figure 5 is a vertical section on line V—V of Figure 2.

Referring to the drawings in detail, I have illustrated in Figure 1 the application of the invention to the return pipe of a vehicle engine cooling system. The numeral 1 des-

ignates the engine which has cylinders 2 surrounded by a water jacket 3. The water is cooled in the radiator 4 which may be of any usual or well known construction. The cooled water passes from the radiator to the jackets through an inlet pipe 5 which may 55 be provided, as is customary, with a flexible pipe section 6 so as to permit the slight relative movement caused by the vibration of the parts to take place without injuring the radiator or loosening the joints of the piping. A pump 7 may be provided for causing the forced circulation of the water, although as will be understood the invention is equally applicable to a thermo-siphon cooling system in which no pump is employed. The heated water from the jacket 3 returns to the radiator through a return pipe section 8 connected to the engine, the pipe section 9 connected to the upper part 60 of the radiator, and the connections between 70 these pipe sections to be described.

In vehicle engine cooling systems it is customary to connect the pipe sections 8 and 9 with a flexible section, usually of rubber hose, and similar to the flexible section 6 65 shown in the inlet pipe. In accordance with my present invention I take advantage of the presence of this flexible section to provide for the mounting of a temperature responsive or other element in the cooling system without the necessity of doing 75 any machine work upon the engine or cooling system or drilling any holes in the metal parts of the system. I accomplish 80 this result by cutting out a portion of the flexible pipe section and introducing a fitting carrying the temperature responsive or other element. As specifically illustrated in the drawings I provide a fitting 10 having nipple portions 11 and 12 of substantially 85 the same diameters as the diameters of the adjacent return pipe sections 8 and 9 respectively, and connect these nipple portions to the return pipe sections by short 90 hose sections 13 and 14. The ends of these 95 hose sections may be secured to the pipe sections and nipples in any desired manner, preferably by the use of hose clamps 15 of any suitable construction. The hose clamps 100 illustrated comprise metal strips bent to enclose the hose and having outwardly turned 105 perforated ears 16 which may be drawn together by bolts 17 so as to cause the clamps

to compress the overlapping portions of the hose section tightly upon the nipples or pipe sections within them. In this way it will be seen that the fitting 10 is permanently and 5 tightly introduced into the cooling system and forms a part of the duct through which the cooling liquid flows; this result being accomplished without disturbing any part of the cooling system except the flexible hose 10 section connecting the parts 8 and 9, which may be cut or removed without difficulty.

The fitting 10 is suitably formed to carry the desired temperature responsive element or other device which is to be introduced 15 into the cooling system. In the construction illustrated a temperature indicating instrument or distance type thermometer is provided having an indicating gage 20 mounted on the vehicle dash 21 or in any other suitable location, the gage being connected by 20 a capillary tube 22 with a temperature responsive element in the form of a fluid filled bulb 23. The fitting 10 is in this instance formed to provide a seat for holding this bulb in the path of the cooling liquid passing through the return pipe. For this purpose the fitting is provided with an enlarged chamber 24 between the nipples 11 and 12, this chamber having an opening 25 at one side thereof and the fitting being formed with a seat 26 around this opening and with a neck 27, the latter being preferably threaded as at 28. The bulb 23 is passed through the opening 25 into the 30 chamber 24, across which it extends diametrically. The bulb is also provided with a flange 29 which is received within the neck 27 and is supported upon the seat 26. Suitable packings 30 and 31 may be introduced 35 above and below the flange if desired. A gland 32 having an opening 33 for the capillary tube 26 is screwed into the threaded part of the neck and compresses the packings 30 and 31 upon the flange 29 and 40 against the seat 26, thereby holding the bulb firmly in position and effectually preventing leakage. The provision of the enlarged chamber 24 to receive the bulb is a valuable feature as it permits the free 45 flow of the cooling liquid through the return pipe. If the enlargement were not provided the presence of the bulb 23 would, in cases where the capacity of the return pipe was only just sufficient to take care 50 of the maximum flow of the cooling liquid, seriously impede such flow and interfere with the proper cooling of the engine. Such a result would be most objectionable 55 as it is well known that insufficient cooling 60 will permit the engine to overheat with results which may be disastrous.

While I have illustrated and described in detail one preferred form and application of my invention it will be understood that the invention may be modified in va-

rious ways and I do not therefore wish to be limited to the particular construction shown but intend to cover my invention broadly in whatever form its principle may be embodied.

Having thus described my invention I claim:

1. A fitting of the character described comprising a pair of nipples connected by a body portion having a larger diameter 75 than said nipples, said body portion having a neck projecting therefrom at substantially a right angle to the axis of the fitting, said neck being provided with an opening, and a temperature responsive element secured in the opening in said neck and projecting into the body portion of the fitting.

2. A fitting of the character described, comprising a pair of nipples connected by a body portion having an enlarged annular 85 portion and a neck projecting therefrom, said neck being provided with an opening, and a temperature responsive element secured in the opening in said neck and projecting into the body portion of said fitting.

3. A fitting of the character described, comprising a pair of nipples, connected by a body portion having an internal transverse sectional area substantially greater than the internal transverse sectional area 95 of said nipples, a neck projecting from said body portion and having an opening therethrough communicating with the interior of said body portion, said neck being provided internally with a seat, a temperature 100 responsive element adapted to be inserted in said neck and body portion and provided with a flange adapted to cooperate with said seat, and a gland adapted to cooperate with said neck for holding said 105 flange in engagement with said seat.

4. A fitting of the character described comprising a pair of nipples connected by a body portion having an internal transverse sectional area substantially greater than the 110 internal transverse sectional area of said nipples, a neck projecting from said body portion and having an opening therethrough communicating with the interior of said body portion, said neck being provided internally with a seat and a threaded end, a temperature responsive element adapted 115 to be inserted in said neck and body portion and provided with a flange adapted to cooperate with said seat, and a gland having a threaded portion adapted to screw 120 into said neck and hold said flange in engagement with said seat.

5. The combination with the cooling system of an internal combustion vehicle propelling motor, of temperature indicating means for indicating to the operator of the vehicle the thermal condition of the engine, said means including a temperature responsive element, and means for introducing 125

said element into said cooling system comprising a fitting having a pair of nipples connected by a body portion having an internal transverse sectional area substantially greater than the internal transverse sectional area of said nipples, said body portion being provided with an opening adapted to receive the temperature responsive element and permit said element to project into said body portion, and flexible hose sections connecting said nipples with ducts of the cooling system.

HARRISON H. BOYCE.
